UNITED STATES PATENT OFFICE

125,566

DESIGN FOR A FOOT COVERING

Donald C. Goulding, Worcester, Mass., assignor to
Handymit Manufacturing Company, Worcester,
Mass., a partnership composed of Francis Cobb
and Donald C. Goulding

Application September 9, 1940, Serial No. 94,902

Term of patent 7 years

To all whom it may concern:

Be it known that I, Donald C. Goulding, a citizen of the United States, residing at Worcester, in the county of Worcester and Commonwealth of Massachusetts, have invented a new, original, and ornamental Design for a Foot Covering, of which the following is a specification, reference being had to the accompanying drawing, forming part thereof, in which—

Fig. 1 is a side elevation of a foot covering showing my new design;

Fig. 2 is a front elevation of the foot covering of Fig. 1; and

Fig. 3 is a rear elevation of the foot covering of Fig. 1.

The design comprises a knitted tubular element closed at one end and adapted to extend over the foot of the wearer. To the underside of this element are secured a very large number of yarn ends to form a thick pad-like sole, the free ends of the yarn being loose, as illustrated, and the thick pad-like sole extending around the heel of the wearer when the tubular element is placed on the foot.

I claim:

The ornamental design for a foot covering, substantially as shown.

DONALD C. GOULDING.
